Patented October 4, 1904.

UNITED STATES PATENT OFFICE.

JOHN S. FREY, OF NEW YORK, N. Y.

DESIGN FOR A WHEEL-KNOB FOR OIL-HEATERS.

SPECIFICATION forming part of Design No. 37,159, dated October 4, 1904.

Application filed September 8, 1904. Serial No. 223,793. Term of patent 7 years.

To all whom it may concern:

Be it known that I, JOHN S. FREY, a citizen of the United States of America, and a resident of the borough of Brooklyn, New York city, in the State of New York, have invented a new, original, and ornamental Design for a Wheel-Knob for Oil-Heaters, of which the following is a specification, reference being had to the accompanying drawings, forming part thereof.

Figure 1 is a face view of a wheel-knob for

oil-heaters, showing my new design. Fig. 2 is a section on the line A B, Fig. 1.

What I claim as new, and desire to secure by Letters Patent, is—

The ornamental design for a wheel-knob for oil-heaters, as shown.

JOHN S. FREY.
